CLASP

Irving Rowen, Bronx, N. Y., assignor to Glen Jewelry Company, Inc., New York, N. Y., a corporation of New York

Application March 16, 1946, Serial No. 654,918

3 Claims. (Cl. 24—71)

1

My invention relates to clasps for bracelets and wrist watch straps or chains and the like, and more particularly to that type of clasp which at all times maintains the opposite ends of the bracelet connected together, but which may be opened fully in order to increase the effective length of the bracelet sufficiently to permit its passage over the hand of the wearer, and which when closed may be adjusted in order to cause the bracelet to properly fit wrists of different circumferences.

One of the chief objects of my invention is to provide a clasp of this type which may be released by merely applying pressure at any point on the top of the clasp, thus making it easier to open than clasps heretofore known which required the wearer to move either a very small button or to lift a member by inserting the fingernail thereunder.

Further objects and advantages of my invention will be apparent from the following description considered in connection with the accompanying drawings, which form a part of this specification and of which:

Fig. 1 is a longitudinal section through a clasp in accordance with my invention in fully opened condition;

Fig. 2 is a sectional view similar to Fig. 1, but with the clasp partly closed;

Fig. 3 is a sectional view similar to Fig. 1 showing the clasp fully closed;

Fig. 4 is a cross-sectional view taken on the line 4—4 of Fig. 3;

Fig. 5 is a cross-sectional view on an enlarged scale taken on the line 5—5 of Fig. 2;

Fig. 6 is a longitudinal section through a clasp showing another embodiment of my invention, the clasp being fully closed;

Fig. 7 is a cross-sectional view taken on the line 7—7 of Fig. 6;

Fig. 8 is a sectional view similar to Fig. 1, but showing another embodiment of my invention;

Fig. 9 is a sectional view similar to Fig. 8 with the clasp shown in closed position;

Fig. 10 is a top plan view on a reduced scale of the clasp shown in Fig. 8; and

Fig. 11 is a cross-sectional view, on an enlarged scale, taken on the line 11—11 of Fig. 9.

Referring to Figs. 1 through 5, reference character 10 designates a base member to one end of which is suitably connected a bracelet or the like 12. Member 10 is curved in order to conform with the curvature of the wearer's wrist. As is more clearly shown in Fig. 5, base member 10 includes a bottom portion 14, upwardly ex-

2

tending side flanges 16, which are turned inwardly at 18 to provide downwardly extending flange elements 20. The lower edge of either or both of the downwardly extending flange elements 20 is formed with ratchet teeth 22.

Pivoted secured to the end of base member 10, opposite the end to which the bracelet 12 is secured, is a link 24, the opposite end of which is pivoted at 26 to a link 28. Either or both of the links 24 and 28 are made of resilient material. As shown, the link 24 is of resilient material and when unconfined is substantially straight, while the link 28 is not resilient and is formed with a curvature substantially the same as that of the base member 10.

The end of link 28 opposite from pivot 26 is provided with a downwardly extending flange or lip 30. This link has sliding engagement with a top member 32 which is in the form of a channel having a web 34 and flanges 36, as is best shown in Fig. 5. As is seen from Fig. 1, the flanges 36 terminate some distance from one end of the member 32 and immediately adjacent to this end of each flange the material is bent back on the inside of the flange, as is shown at 38 in Fig. 5. The length of the parts 38 is such that sufficient clearance is left between their upper ends and the inside of the web 34 to accommodate the link 28, which may slide longitudinally between the web and the parts 38, the lip 30 on the link 28 preventing complete separation of the link from the member 32. The material of the flanges 36, except where it is bent inwardly to form the pieces 38, is bent outwardly at right angles to the flanges to form additional flanges 40 which, when the clasp is closed, slide underneath the flanges 20 on the base member 10. The flange 40 which cooperates with the flange 28 carrying the ratchet teeth 22 is formed with a tooth or projection 42 for engaging the ratchet teeth.

The other end of the member 32 is suitably connected to the opposite end of the bracelet 12.

The above described device operates as follows: With the parts in the position shown in Fig. 1, or with the link 24 pivoted still farther in a clockwise direction with respect to the base member 10, the bracelet is in its most extended condition and may be slipped over the hand of the wearer. Thereafter the top member 32 is grasped by the other hand and is manipulated so as to pivot the link 24 in a counterclockwise direction with respect to the base member 10 until the end of the top 32 enters between the flanges 20 of the base member. Inasmuch as the

outwardly extending flange 40 on the top member do not extend all the way to the end of this member, the end of the latter may enter freely between the flanges 20 on the base member. Thereafter, the top member 32 is slid into the base member, the flanges 40 of the former sliding below the flanges 20 of the latter. During this movement the tooth 42 on the flange 40 of the top member slides over the teeth 22 of the ratchet. Also, as the top member is slid into the base member, the normally straight link 24 is deflected so as to have the same curvature as that of the base and top members and consequently the resiliency of the link 24 causes it to force the top member upwardly within the base member, thus assuring engagement of the tooth 42 with the ratchet teeth 22.

The top member is slid into the base member a distance sufficient to cause the bracelet to properly fit the wrist of the wearer and obviously the telescoping of the two members can be stopped at any point after the tooth 42 has engaged the ratchet teeth.

When it is desired to remove the bracelet, pressure applied by the finger at any point along the top of the member 32 causes it to move slightly downwardly within the base member against the spring effect of the resilient link 24, thus releasing the tooth 42 from engagement with the ratchet teeth 22 and, while so disengaged, the top member may be slid out of the base member. It will thus be seen that it is not necessary to apply a releasing force to a small button or the like, or to lift any part by means of the fingernail.

The embodiment illustrated in Figs. 6 and 7 differs from that shown in the preceding figures in that none of the links are made of resilient material, but a separate spring 50 is secured within the base member 10 and serves, when the top 32 is slid into the base member, to force the flanges 40 of the former upwardly against the flanges 20 of the latter so as to engage the tooth 42 with the ratchet teeth 22. In this embodiment, the spring 50, which in cross-section has the shape best shown in Fig. 7, may be secured to the bottom portion 14 of the base member in any suitable manner, such as by being riveted or spot welded thereto. The operation of this embodiment is the same as that disclosed above and hence a repetition of the description of the opening and closing of the clasp is not necessary.

The embodiment illustrated in Figs. 8 through 11 differs from those previously described in that the base member is slidably connected with the first link, while the top member is pivotally connected to the second link.

Referring to these figures, reference character 50 designates generally the base member having a bottom 52 and side flanges 54. The upper edges of the flanges 54 are turned inwardly to provide downwardly extending flange elements 56, one or both of which is provided with a series of ratchet teeth 58.

The first link 60 is provided with an enlarged end 62, the width of which is substantially the same as the interior dimension between the flanges 54 on the base member. A tooth 61 extends upwardly from one corner of the enlarged end 62. The link 60 is made of resilient material and a spring finger 64 is preferably struck out of the enlarged end 62, the free end of this finger bearing against the bottom 52 of the base member so as to force the sides of the enlarged end up against the lower edges of the downwardly extending flanges 56 and to maintain tooth 61 in

engagement with teeth 58. The end of the bottom 52 of the base member is formed with an upstanding lip 66 which serves as a stop which is engaged by the end of the spring finger 64 when the link 60 is slid to the extended position shown in Fig. 8, thus preventing complete withdrawal of the link 60 from the base member.

Pivottally connected to the link 60 is a second link 68, the opposite end of which is pivotally connected to one end of the top member 70. This top member is formed with a pair of downwardly extending flanges 72 extending the entire length of the member, the distance between the outer surfaces of which is substantially equal to the interior distance between the downwardly extending flanges 56 on the base member. A pair of outwardly extending flanges 74 are provided at the lower edges of the flanges 72 and are adapted to slide underneath the lower edges of the flanges 56. As will be seen more particularly from Figs. 8 and 10, the flanges 74 do not extend the entire length of the top member 70 but terminate at a distance from one end thereof which is substantially equal to the length of the enlarged end 62 of the link 60.

With the parts in the position shown in Fig. 8, the clasp is fully open and the bracelet may be fully extended. In order to close the clasp the link 68 and the top member 70 are folded downwardly until the left ends thereof are within the flanges of the base member 50. In this position the flanges 74 of the top member are closely adjacent to the end of the enlarged portion 62 of the link 60, and hence are a short distance to the right of the base member 50. Thereafter, the links 60 and 68 and the top 70 may be slid into the base member, the enlarged end 62 sliding underneath the flanges 56 with the tooth 61 engaging successive teeth of the ratchet 58. Also, the flanges 74 of the top member slide underneath the flanges 56 of the base member. The spring finger 64 urges the tooth 61 into engagement with the teeth 58 and consequently the link 60, the link 68 and the member 70 are prevented from moving to the right. Thus, the length of the bracelet may be adjusted to accommodate the circumference of the wrist of the wearer. The link 68 and the top 70 are prevented from unfolding out of the base member when the clasp is closed due to the fact that the flanges 74 on the top member are underneath the flanges 56 of the base member.

When it is desired to open the clasp, pressure is applied to the top member which pressure is transmitted through the second link 68 to the link 60, thus moving the latter downwardly against the force of spring finger 64 and disengaging the tooth 61 from the teeth 58. With the parts in this position the links 60 and 68 and the top member 70 may be slid to the right until the flanges 74 on the top member are beyond the flanges 56 on the base member, whereupon the clasp may be fully opened.

While I have described several preferred embodiments of my invention, it is to be understood that this has been done for purposes of description only and the scope of my invention is not to be limited thereby but is to be determined from the appended claims.

What is claimed:

1. In a bracelet clasp, a channel member adapted to be attached to one end of a bracelet, said channel member having a transverse wall, and vertical side flanges forming a U-shaped

cross section and an inturned element on at least one of said flanges spaced from said transverse wall to receive a slide flange therebetween, elements adapted to be nested in said channel member comprising a second member adapted to be connected to the other end of the bracelet, and a pair of links pivotally connected together, one of said links being pivotally connected to one of said members and the other link being slidably connected to the other of said members; said links being receivable in said channel member between said side flanges, and said second member being slidable into said channel member and having a flange at least as long as the sliding distance positioned to slide in the space between said inturned element and said transverse wall for preventing the parts from unfolding, cooperating latching elements on the contacting surfaces of said inturned element and on one of the elements adapted to be nested and which is slidable in said channel member between said inturned element and said transverse wall, engageable upon displacement of said one of said nestable elements toward the open side of said channel to prevent said second member from sliding outwardly and being releasable when said second member is pressed toward nested position in said channel member, one of said latching elements comprising ratchet teeth shaped to permit inward sliding adjustment of said second member.

2. In a bracelet clasp, a channel member adapted to be attached to one end of a bracelet, said channel member having a transverse wall and side flanges forming a U-shaped cross section and an inturned element on at least one of said flanges spaced from said transverse wall to receive a slide flange therebetween, a second channel member adapted to be connected to the other end of the bracelet and to slide within the first channel member, a pair of links pivotally connected together, one of said links being pivotally connected to said first channel member and the other link being slidably connected to the second channel member, said links being receivable in said first channel member between said side flanges, and said second channel member being slidable into said first channel member and having a side flange at least as long as the sliding distance positioned to slide in the space between said inturned element and said transverse wall for preventing the parts from unfolding, cooperating latching elements on the contacting surfaces of said inturned element and the side flange of said second channel member engageable upon displacement of said second channel member toward the open side of said first channel member to

prevent said second channel member from sliding outwardly, one of said latching elements comprising ratchet teeth shaped to permit inward sliding adjustment of said second channel member, said links tending to maintain said latching elements in engagement and being deformable to release said elements when said second channel member is pressed toward nested position in said first channel member.

5 3. In a bracelet clasp, a channel member adapted to be attached to one end of a bracelet, said channel member having a transverse wall and side flanges forming a U-shaped cross section and an inturned element on each of said flanges spaced from said transverse wall to receive a side flange therebetween, a second channel member adapted to be connected to the other end of the bracelet and to slide within the first channel member, a pair of links pivotally connected together, one of said links being pivotally connected to said first channel member and the other link being slidably connected to the second channel member, said links being receivable in said first channel member between said side flanges, and said second channel member being slidable into said first channel member and having outwardly extending side flanges at least as long as the sliding distance positioned to slide in the space between said inturned elements and said transverse wall for preventing the parts from unfolding, cooperating latching elements on the contacting surfaces on one of said inturned elements and the cooperating side flange of said second channel member engageable upon displacement of said second channel member toward the open side of said first channel member to prevent said second channel member from sliding outwardly, one of said latching elements comprising ratchet teeth shaped to permit inward sliding adjustment of said second channel member, said links tending to maintain said latching elements in engagement and being deformable to release said elements when said second channel member is pressed toward nested position in said first channel member.
